UNITED STATES PATENT OFFICE.

ELWOOD H. CONRAD, OF TREVORTON, PENNSYLVANIA.

MEANS FOR ATTACHING AND DETACHING LIGHT-GLOBES.

1,157,617.

Specification of Letters Patent.

Patented Oct. 19, 1915.

Application filed April 23, 1915. Serial No. 23,459.

To all whom it may concern:

Be it known that I, ELWOOD H. CONRAD, a citizen of the United States, residing at Trevorton, in the county of Northumberland and State of Pennsylvania, have invented certain new and useful Improvements in Means for Attaching and Detaching Light-Globes, of which the following is a specification.

10 This invention relates to means for attaching and detaching light globes—such as incandescent electric light globes—to or from their supports; the main object of the invention being to provide means for efficiently supporting the globe during the vertical movement of the handle and consequently gripping the same at a gradually increasing degree simultaneous with the fastening operation.

20 Another object is to provide means of the above character which will obviate the danger of breakage of the globe structure or the usual protuberance formed on the under side thereof.

25 A further object of the invention is to provide a device of the type in question that is simple in construction, it consisting of but a few simple parts, whereby it is believed that the same may be manufactured at a comparatively low cost.

The above and other objects which will become apparent are accomplished by such means as are shown in their preferred form in the accompanying drawings, described in 35 the following specification and more specifically pointed out in the appended claims.

In the accompanying drawings wherein like numerals designate like parts throughout the several views, Figure 1 is a side elevation of my invention showing the handle portion broken away, the gripping jaws being shown in engagement with an ordinary electric globe. Fig. 2 is a plan view of my invention. Fig. 3 is a vertical sectional view 45 showing parts thereof broken away. Fig. 4 is a detail view showing parts of the device broken away. Fig. 5 is a perspective view of my invention illustrating more clearly the mode of attaching the light globe to its respective socket.

In the preferred embodiment of my invention, I have shown the same used in connection with an ordinary electric light globe A.

55 My invention, generally, comprises a

body structure 10 which has a series of cut-outs 11 arranged adjacent its perimetral face, and a central recess 12 in its upper face, and which performs certain functions that will presently appear. Suitable curved arms 13 are employed, the lower ends of which are received within the cut-outs 11 and secured rigidly to the body structure through the medium of the fastening members 14. I have found it advantageous to construct the arms 13 of a resilient material, preferably of a ductile sheet metal in order to compensate for the relative movement of the gripping structures, presently described.

In order to effectually engage the adjacent portion of the light globe during the operation of my invention, an improved gripping structure is employed which consists of sections 15 and 16 that are arranged in the manner clearly shown in Fig. 2. It will be noted that the section 15 may be formed integral with certain of the arms 13 while the other section may be correspondingly formed with the remaining arm in order that they may be held relatively movable in relation to one another. One end of the section 16 is bent to form a sleeve portion 17 that has its intermediate structure cut away to a suitable degree in order to receive a sleeve portion 18 formed on the adjacent end of the section 15. The coincident apertures provided by the respective sleeve portions receive a fastening member 19 in order to form a fulcrum about which the respective sections operate.

As will be noted upon reference to Fig. 2 the opposite ends of the respective sections of the gripping structure are normally spaced apart by the tension exerted by the respective arms 13, so that the device is rendered capable of receiving light globes of varying diameters, and resiliently gripping the globes after they have been positioned in place. Suitable sections of cushion material 20 and 21 are arranged on the inner faces of the arms 13 and the sections 15 and 16 respectively in order to engage the fragile light globe structure and obviate the danger of its breakage.

With view of accommodating suitable operating means for the device, a collar structure 22 is provided, and it receives the body portion 10 as shown in Fig. 3. Suitable transverse fastening means 23 are employed for securing the body portion in rigid rela-

tion to the collar. The interior bore of the collar below the lower terminus of the body 10 is provided with screw threads, for accommodating the correspondingly formed upper portion of a handle member 24. This mode of fastening the handle to the collar has proven very efficient in practical use, as the handle is held in movable relation to the collar in order that it may coöperate with suitable means carried on the respective gripping sections 15 and 16 for operating the latter at a gradually increasing extent during the fastening operation of the globe. It is to be realized however that the method of fastening the said handle to the collar may be varied without departing from the scope of my invention.

Suitable studs 25 and 26 are secured to the respective sections 15 and 16 adjacent their free ends in order to accommodate the respective ends of a flexible operating member 27. The ends of the flexible member are secured to the adjacent studs, that portion of the fastening member adjacent the end which is secured to the stud 25 being brought to extend over the stud 26, downwardly to engage the fastening member 28 on the handle. From the member 28, the respective portion of the operating member is brought upwardly to extend over the stud 25 and has its terminal fastened to the stud 26 in any suitable manner. It is now recognized that the independent movement of the handle in one direction will exert a pressure upon the stud members, through the medium of the member 27 that is sufficient to contract the respective free ends of the gripping sections. This operation may be more concisely illustrated upon reference to Fig. 1 of the drawings. The globe A is first arranged in connection with the device in the manner shown, its lower portion resting on the curved portions of the arms 13 and the protuberance on its under face projecting into the recess 12. The gripping sections 15 and 16 are normally held about the sides of the globe by action of the tension exerted of the arms 13, yet this tension is not sufficient to prevent the independent rotary movement of the globe. During the vertical movement of the handle the globe structure will be held in a secure position through the instrumentality of the respective arms and the lateral displacement thereof will be prevented by the gripping structures. As the globe is secured into its respective socket, it will naturally resist the corresponding rotation of the gripping structures and the collar 22. This will allow the handle to move freely, and by so doing, it will draw the operating member 27 taut and exert a pressure upon the respective stud members that is sufficient to contract the ends of the gripping sections. Thus it will become apparent that the globe

is gripped at a gradually increasing degree simultaneous with the fastening operation and that the same may be positively and effectually secured in place.

In reducing my invention to practice I find that the form referred to herein as the most practical and preferred embodiment is the most efficient, but realizing that certain conditions will necessarily vary in concurrence with the adoption of my device, I desire to emphasize the fact that various minor changes in details of construction and proportion of parts may be resorted to when required, without sacrificing any of the advantages of my invention as defined in the appended claims.

Having thus fully described my invention, what I claim as new and desire to secure by Letters Patent is:

1. In a device of the character described, a body structure, resilient arms carried by said body structure, relatively movable gripping structures, carried by said arms, a handle movably connected to said body and flexible means connecting the free ends of said gripping structures and said handle whereby the independent rotation of said handle will cause the contracting of the free ends of said gripping structures, substantially as described.

2. In a device of the character described, a body structure, resilient arms carried by said body structure, gripping sections carried by said arms, one end of said gripping structures being hingedly connected together, a handle movably connected to said body structure, and means connecting the free ends of said gripping sections and said handle, substantially as described.

3. In a device of the character described, a body structure, arms extending from said body structure, gripping members carried by said arms, one end of said gripping members being hingedly connected, a collar secured to said body structure, a handle in movable relation to said collar, and flexible means connecting the free ends of said gripping members and said handle for the purpose specified.

4. In a device of the character described, a body structure, said body structure provided with a series of cut-outs, a plurality of resilient arms, the lower ends of said arms seating in said cut-outs, means to secure said arms to said body structure, gripping sections carried by said arms, means hingedly connecting one end of said gripping sections, studs secured to said gripping sections, adjacent their free ends, a collar carried by said body structure, a handle in movable relation to said collar, and flexible means connecting said stud members and said handle for the purpose specified.

5. In a device of the character described, a body structure, resilient arms projecting

upwardly from said body portion, gripping members carried by said arms, means hingedly connecting one end of said gripping members, a handle, and means operated by 5 said handle for contracting the free ends of said gripping members, substantially as described.

6. In a device of the character described, a body structure, a series of resilient arms 10 secured to said body structure, gripping members carried by said arms, means hingedly connecting one end of said gripping members, the other end of said gripping members being normally spaced apart, a 15 handle member and means operated by said handle member for contracting the free ends of said gripping members, substantially as described.

7. In a device of the character described, a 20 body structure, a collar carried thereby, a handle movably secured to said collar, a series of resilient arms carried by said body structure, means to secure said arms to said body structure, gripping members integral 25 with said arms, means hingedly connecting one end of said gripping members the other end of said gripping members being normally spaced apart, cushion means arranged on said arms and said gripping members, 30 and means operated by said handle for con-

tracting the free ends of said gripping members, substantially as described.

8. In a device of the character described, a body structure, said body structure provided with a series of cut-outs, a recess provided in the upper face of said body structure, a series of resilient arms, the lower ends of said arms secured in said cut-outs, 35 a collar arranged about said body structure, a handle movably connected to said collar, 40 gripping members integral with said arms, means hingedly connecting one end of said gripping members, the opposite ends of said gripping members being normally spaced apart, stud members secured to said gripping members adjacent their free ends, 45 cushion means secured to the inner faces of said arms and said gripping members, and a flexible member connecting said stud members and said handle whereby the independent rotation of said handle will cause the contraction of the free ends of said gripping members, substantially as described. 50

In testimony whereof I affix my signature in presence of two witnesses.

ELWOOD H. CONRAD.
